Attorney

UNITED STATES PATENT OFFICE.

ALFRED A. ANDERSON, OF JAMESTOWN, NEW YORK.

JOINT FASTENING FOR FURNITURE.

Application filed March 10, 1922. Serial No. 542,557.

To all whom it may concern:

Be it known that I, ALFRED A. ANDERSON, a citizen of the United States, residing at the city of Jamestown, in the county of Chautauqua and State of New York, have invented certain new and useful Improvements in Joint Fastenings for Furniture, of which the following, taken in connection with the accompanying drawings, is a specification.

The invention relates to fastening devices for furniture, and is an improvement upon my furniture joint-fastenings as shown in my Letters Patent No. 1,069,994, patented 15 August 12, 1913, and No. 1,071,542, patented August 26, 1913; and the object of the present improvement is to further simplify and strengthen my joint-fastening so that while it is self-locking, it provides as it were a 20 double truss construction in its wedging arrangement while occupying an exceedingly small amount of space, thereby accomplishing the greatly desirable qualities in a fastening of this type, that is, a joint fastening of great strength which occupies small 25 space and particularly as to the depth or thickness of the fastening so that when placed on the rear side of a dresser or other article of furniture, it does not project and 30 mar the wall or other surfaces against which the article of furniture may be placed; and the invention consists in the novel features and combinations hereinafter set forth and claimed.

In the drawings, Figure 1 shows an elevation of the furniture fastening attached to the different parts of a piece of furniture to attach one part to the other. Fig. 2 is a plan view of the two inter-engaging parts 40 of the fastening with their spaced return bend inturned flanged edges. Figs. 3 and 4 show a plan view, and edgewise and end elevations of the new form of wedge with its lengthwise tapered spaced outturned flanged edges. Fig. 5 is an end elevation of the complete joint-fastening with the wedge in position in the inter-engaging portions of said fastening; and Fig. 6 is a lengthwise sectional view of the same at line 6-6 in 45 Fig. 1 showing the fastening attached to two portions of a piece of furniture and showing the central interlocking ends of the engaging parts and the wedge extending down over and locking the same in the engaged 50 position; and Fig. 7 is a lengthwise sec-

tional view at line 7-7 in Fig. 1 showing the outwardly flanged tapered edges of the wedge in holding engagement beneath the spaced return bend edges of the two inter-engaging parts of the furniture fastening. 60

Like characters of reference refer to corresponding parts in the several views.

The joint-fastening consists of the upper outwardly flanged attaching plate 10 with the spaced inturned return bend edges 11 65 with the bottom end flange 12 in the crosswise spaced position central therebetween; and the lower outwardly flanged attaching plate 13 with the lengthwise spaced inturned return bend edges 14 similar to plate 10 and 70 in alinement with the spaced return bend edges of said plate 10, and a spaced return bend hooked flange 15 intermediate between the flanges 14 crosswise on the end adjacent the flange 12 to hook over the same in holding engagement. 75

The inter-engaging attaching plates 10 and 13 are provided with attaching screw holes 16 for attachment to parts 22 and 23 each side of the furniture joint in inter-hooking relation as shown in Figs. 1 and 6. This brings the spaced return bend flanged lengthwise edges 11 and 14 into alinement so as to provide a continuous lengthwise flange on each edge which turns outwardly 80 from the surfaces of the furniture parts and then inwardly in spaced return bend alinement to a spaced distance from the surfaces of the plates 10 and 13 as shown at 18. 85

The wedge 19 comprises the channel-shaped central portion 20 and the spaced out-turned tapered flanged edges 21 and 22 which engage beneath the spaced return bend flanged edges 11 and 14 at each side so that when driven to place, each of said return bend edges forms as it were a tubular holding portion substantially as strong as in my former furniture fastenings, in addition to the central bridging channel-shaped portion 20 which extends down over the 100 interhooking portions 12 and 15, locking them firmly in the interengaging position, as shown in my application for Letters Patent, Ser. No. 536,792, filed February 15, 1922. 105

It is apparent that the construction permits the flattening of all the parts so that the complete three-part furniture fastening when assembled in holding position takes a minimum amount of space with greatly 110

increased holding strength and consequent rigidity in the holding of the parts 22 and 23 each side of the joint 17.

It is apparent that each of the three parts

5 10, 13 and 19 can be quickly and economically struck up from the sheet metal by means of suitable dies, thereby providing an exceedingly strong and convenient furniture fastening at low cost.

10 What is claimed as new is:

1. In a furniture joint fastening, a pair of members arranged in end to end relation and each having a body and side flanges which latter extend outwardly and then inwardly over the bodies and have their free edges extended inwardly toward and spaced from the bodies, interengaging means between the adjacent ends of the members, and a wedge composed of a metal plate having its sides turned outwardly at approximately right angles and then turned to lie parallel to the plate and finally turned inwardly to extend toward the plate, the side parts of the plate parallel thereto seating on the bodies of the pair of members and the inwardly turned parts of the plate being received between the outwardly and inwardly extending parts of the side flanges of the pair of members, the free edges of the in-

wardly turned parts of the plate being longitudinally inclined to wedge against the inwardly extending parts of the side flanges of the bodies.

2. In a furniture joint fastening, a pair of members arranged in end to end relation and each having side flanges which extend outwardly and inwardly and finally towards the bodies of the members in spaced relation to the bodies, to form side flanges of approximate J-shape in cross-section, interengaging means between the adjacent ends of the members, and a wedge having its sides formed with reversely disposed parts of J-shape in cross section which seat on the bodies of the members and which engage between the outwardly and inwardly extending parts of the J-shaped side flanges of the members, the free edges of the J-shaped sides of the wedge being longitudinally inclined to wedge against the inwardly extending parts of the side flanges of the bodies.

In testimony whereof I have affixed my signature in the presence of two witnesses.

ALFRED A. ANDERSON.

Witnesses:

THEO. THOMAS HAAG,
CORINNE V. SWANSON.
